UNITED STATES PATENT OFFICE.

FRANK B. MORRISON, OF MARION, OHIO, ASSIGNOR TO THE POWER MANUFACTURING COMPANY, OF MARION, OHIO, A CORPORATION OF OHIO.

GOVERNOR.

Application filed March 18, 1926. Serial No. 95,661.

This invention relates to improvements in governors for internal-combustion engines. It finds practical value in an engine which in operation carries an intermittent load 5 of given frequency duration and value, a state of things which obtains in the drilling of wells and the like. In that particular application I shall describe it.

In the accompanying drawings Fig. I is 10 a view in side elevation, showing diagrammatically well-drilling apparatus, in which in association with the engine shaft appears the governor in which my invention centers; Fig. II is a view to a larger scale showing 15 in vertical section the governor.

Referring first to Fig. I, 20 indicates the walking beam of the well-drilling apparatus. From one end, the right-hand end as here presented, the drilling tools are hung 20 by the suspensory member 21. The opposite left-hand end of the walking beam 20 is linked to a crank-arm 22 upon the shaft of a band wheel 23. The band wheel is driven through belt 24 from engine shaft 25, and the engine shaft 25 will be understood 25 to be the shaft of an internal combustion engine indicated at 26. The governor 27 is in Fig. I shown in association with the engine shaft and this governor is in detail 30 shown in Fig. II.

Shaft 1 of this governor is caused to rotate in unison with the engine shaft 25, and to that end the two shafts may conveniently be connected by a sprocket-chain drive not 35 shown. Manifestly when the two shafts are so caused to rotate in unison the speed of rotation of shaft 1 of the governor will vary with the speed of the engine shaft. Rotation of shaft 1 effects rotation of the 40 vertically standing governor shaft 2, geared to it, and reciprocation of a plunger within a bearing block 3 through gears and cam 3^A. Aligned with and operated by the plunger within bearing block 3 is the 45 plunger 4 of the pump by which fuel is injected to the engine cylinder. A vertically adjustable wedge block 5 is interposed between the aligned plungers. As the wedge rises, the plunger of the injection 50 pump is shifted against spring tension, in direction away from the plunger in the bearing block 3—that is, to the left, as seen in the drawing. Accordingly, as the wedge

rises, the effective stroke of the plunger of the injection pump is shortened, and the 55 quantity of fuel supplied per stroke is diminished. With the engine then operating under a continuing load, the tendency is to diminution of speed.

The vertically standing governor shaft 2 carries, rigid with itself, a collar 6, and upon collar 6 are mounted two oppositely placed, weighted bell-crank levers 8. The shaft carries also a collar 7, movable longitudinally upon it, and the shaft is freely rotatable within the collar. Springs 9 and 10, backed by a rigidly sustained block 11, bear from above upon collar 7, and under the spring tension so afforded the collar 7 bears upon the inner arms of the bell-crank levers 70 8. The bell-crank levers 8 are so weighted and so arranged that under the centrifugal force brought to bear by shaft rotation the free arms tend to separate, and in so doing to raise collar 7, against the tension of one 75 or both of springs 9 and 10. The collar 7 is linked to a lever 12, and lever 12 in turn is linked to wedge 5, and through such connected instrumentalities, rise of collar 7 effects a corresponding rise of wedge 5, a 80 proportionate diminution in the length of the stroke of the pump plunger, and (other things being equal) a corresponding diminution in the quantity per stroke of fuel injected into the engine cylinder. 85

The invention lies in the spring backing of collar 7. A plurality of springs is employed—in this instance, two—and the springs come successively and cumulatively into play, as the collar 7 rises from its lowest position. When with such spring backing for collar 7 the engine is in service under a load which increases to a maximum and then immediately drops to a minimum—as is the case in well-drilling operations—the response of the weights to centrifugal force is retarded, and with such retardation the response of the descending tool to gravity is enjoyed in larger measure. 90 95

The number of springs may conveniently 100 be two, as shown in the drawings. They are conveniently helical springs of unequal diameters, concentrically arranged about the axis of shaft rotation. One of them comes into play before the other, and this 105 is conveniently achieved by forming one of

them longer than the other. And in this particular instance, the inner spring 9 is longer and lighter than the outer spring 10.

Consider, now, the conditions when an engine equipped with this improvement is used in drilling a well. The engine acts upon one end of a vertically swinging walking-beam, from the opposite end of which the drill is hung. The engine pulls its end of the beam downward, and in so doing raises the drill. During this up stroke of the drill the load on the engine is greatest, its speed is correspondingly low, and the light spring 9 is effective to hold the centrifugal governor collapsed and the wedge 5 in its lowest position, where the stroke of the fuel-injection plunger is longest. Immediately when the lowest point is reached in the downward swing of that end 20 of the walking beam to which the engine is attached, and the return upward swing begins, the load upon the engine falls to a minimum. But for my invention the governor would immediately become effective, to cut down engine speed, and retard the swing of the beam. But it is most desirable that the beam be not so retarded; it is most desirable that the beam be free, and that the drill descend, in unrestrained response to gravity.

By providing a plurality of springs which come successively into play, the spreading weights must overcome the inertia of each spring newly subjected to compression, and in overcoming such inertia, the moving weights lose inertia of their own. The consequence and effect is that the swing of the weights is delayed, hence the speed of the engine is increased, due to a constant supply of fuel with a reduced load, and correspondingly the force of gravity is allowed to be effective for drilling.

The governor functions in its normal manner, to render the supply of fuel in the

main proportionate to the desired speed, and to cause the well-drilling tool to rise and descend in constant periodicity. The invention brings into the recurrent rise and descent of the tool one qualification: as descent begins, the momentary arrest in governor operation allows the tool to fall with relative freedom. Fuel is saved and the operation of drilling is improved. Subject to this qualification, the governor functions in well-known manner and still ensures the desired uniformity in the stroke of the tool.

The invention has been described in particular application to an engine equipped with a pressure pump for injecting the fuel into the cylinder; but, manifestly, the invention is applicable similarly to control the supply of fuel, whether to the carburetor of a gas engine, or to fuel-introducing means of any sort.

The effective tension of the springs 9 and 10 may be made variable by making the backing block 11 adjustable longitudinally of the shaft 2. This adjustability is indicated in that the block 13, upon which the block 11 bears, is adapted to be screwed in and out of its mounting and in the direction of the axis of shaft 2.

I claim as my invention:

In apparatus for drilling bores in the earth the combination of a vertically swinging walking beam, a tool hung from the walking beam at one end and an internal combustion engine operatively engaging the beam at its other end, said engine being provided with a fuel control and with a centrifugal governor controlling such fuel control, and means for opposing the centrifugal swing of the governor, such means presenting to the governor when in the course of its swing an abrupt increase of resistance.

In testimony whereof I have hereunto set my hand.

FRANK B. MORRISON.
